US00D831045S

(12) **United States Design Patent** (10) **Patent No.:** **US D831,045 S**
Leininger et al. (45) **Date of Patent:** **** Oct. 16, 2018**

(54) **DISPLAY SCREEN OR PORTION THEREOF WITH GRAPHICAL USER INTERFACE**

(71) Applicant: **AGCO Corporation**, Duluth, GA (US)

(72) Inventors: **Jay Leininger**, Hesston, KS (US);
Joshua Ekholm, Hesston, KS (US);
Jared Koch, Hesston, KS (US); **Gerald R. Johnson**, Hesston, KS (US)

(73) Assignee: **AGCO Corporation**, Duluth, GA (US)

(**) Term: **15 Years**

(21) Appl. No.: **29/641,630**

(22) Filed: **Mar. 23, 2018**

(57) **CLAIM**

The ornamental design for a display screen or portion thereof with graphical user interface, as shown and described.

DESCRIPTION

FIG. 1 is a front view of a graphical user interface for a display screen or portion thereof showing our new design. FIG. 2 is a front view of another embodiment of our new design.

FIG. 3 is a front view of another embodiment of our new design; and,

FIG. 4 is a front view of another embodiment of our new design.

The dot-dash lines showing a display screen or portion thereof illustrate portions of the article and form no part of the claimed design.

1 Claim, 3 Drawing Sheets
